UNITED STATES PATENT OFFICE.

FRAZER GERARD, OF ST. PAUL, MINNESOTA.

VENTILATING DEVICE.

1,048,064.

Specification of Letters Patent.

Patented Dec. 24, 1912.

Application filed February 26, 1912. Serial No. 680,016.

To all whom it may concern:

Be it known that I, FRAZER GERARD, a citizen of the United States, residing at St. Paul, in the county of Ramsey and State of 5 Minnesota, have invented certain new and useful Improvements in Ventilating Devices, of which the following is a specification.

My invention relates to a ventilating device, more especially to such a device applied to railway cars or street cars.

It is the object of my invention to provide a ventilator which shall operate constantly to drain the foul air from the compartment of the car without creating a draft or permitting the air from outside to blow in and, consequently, without admitting dust or smoke from outside. In accomplishing these objects I employ primarily a draft 20 casing placed adjacent a wall of the car, said casing being extended longitudinally alongside said wall and having an expanded or funnel shaped end turned in the direction of movement of the car, which end will thus 25 be positioned to be forced against the atmosphere as the car moves along and will collect and compress a current of air which will travel through the casing or passage at a high speed. Within this outside casing I 30 place a series of tubular members having one end penetrating the wall of the car so as to open inside thereof. These members are curved at right angles parallel to the direction of the car wall and extend longitudinally 35 through the casing. They are provided with means opening the same into the chamber of said casing for collecting and compressing a part of that current in the tubes themselves, which compressed inner 40 currents will act to draw air from the car and deliver the same from the end of the tubes into and out of the end of the casing.

The full objects and advantages of my invention will appear in connection with 45 the detailed description thereof and are particularly pointed out in the claims.

In the drawings illustrating the application of my invention in one form, Figure 1 is a front elevation of a portion of the car 50 having my invention applied thereto, viewed

from the front or away from the direction of movement of the car. Fig. 2 is a fragmentary plan of a portion of a car having my invention applied thereto with the casing shown in section. 55

Upon the roof of a car 10 provided with the usual cupola or longitudinally raised central portion 11 is secured a trough 12 which may be rectangular or square in cross section and includes a passage way 13. 60 Preferably the trough 12 will be applied to both sides of the cupola 11. At the front of the trough is a funnel like expanded portion 14 adapted to present a considerable area to the atmosphere as the car moves 65 through it and thereby to gather together and compress a strong current of air in the passage 13, as indicated by arrows in Fig. 2. The funnel portion 14 may, if desired, be made removable so that when the 70 car is turned around the funnels can be taken from one end of the casings 12 and placed on the other end of said casings. Positioned within the casing 12 is a series of pipes 15 each being turned at right 75 angles as indicated at 16 in Fig. 2 and opening through apertures 17 in the wall of the car into the inside of the cupola 11. The pipes 15 after the aforesaid right angle bend extend longitudinally in the casing 12 pref- 80 erably as close to the inside wall of the casing as is possible while at the same time making a smooth curved bend at the point 16. On the side of these pipes at a point somewhat removed from the bend 16 and 85 aperture 17 are formed openings 18. To the edge of these openings away from the said bend 16 and aperture 17, that is, away from the direction of travel of the car and the casing, raised flange-like hoods 19 are se- 90 cured, which hoods, as clearly shown in Fig. 2, extend into the passage 13 some little distance beyond the walls of the pipes 15, thus presenting a funnel-like mouth direct- 95 ed toward the funnel or advancing end of the casing 12.

The method of operation of my ventilating device will be clear from an inspection of Fig. 2. As the car moves through the air a considerable amount of air is gathered 100

together in the funnel 14 and compressed and travels through the passage 13 at a speed which approximates that at which the car is moving. As this body of air moves 5 through the passage 13 it reaches the pipes 15 where the area of the passage is diminished to the extent of the combined cross-sectional area of the entire series of pipes used. This further compresses the current of 10 air and when it reaches the openings 20 beneath the hoods 19 it expands into these openings, passes through the opening 18 and on through the continuation of pipes 15. The effect of the stream of air moving through 15 opening 18 is to take frictional hold of the air in pipes 13 ahead of the opening 18 and draw a portion of this air along with it. Air from the car passes in to take the place 20 of that carried along and powerful suction currents are set up which draw air from the car through the openings 17. There is thus a constant current of air in one direction drawn from the inside of the cupola of the car without possibility of any of 25 the outside air with its accumulations of dust and dirt passing back into the car. Air will enter the car to take the place of that leaving it through minute apertures in the walls and around the car windows, or 30 if desired special apertures provided with air strainers may be employed for this purpose.

While I have shown this ventilator as applied to the side of the car cupola, since 35 this is a convenient and satisfactory place, I do not wish to be limited to such an application, as the principles of the invention make it possible to apply the device to any other portion of the car, as, for example, 40 just below the floor if this were found desirable. It will readily be seen that my ventilator is simple in construction and can readily be applied to cars as now built without extensive remodeling. It requires no 45 power to operate the same, the actuating force being the ordinary movement of the car through the atmosphere. Instead of employing ventilators at both sides of the car it is practicable and is contemplated by 50 me to use but a single ventilator at one side of the car, in which case the ventilator at the other side of the car may be turned the other way and the ventilator turned away 55 from the direction of movement of the car can be closed so that the ventilating system can be used whichever direction the car may go without turning the car around.

I claim:

1. A car ventilator comprising a casing 60 open at both ends and extending in the direction of travel of the car, tubular members extending longitudinally within the casing and through the wall of the car to the interior thereof, and means for collecting a

portion of the air currents passing through 65 the passage within the casing and causing them to enter the tubular members at a point at the rear of the point of entrance thereof into the car.

2. A car ventilator comprising a casing 70 open at both ends and extending in the direction of travel of the car the front end of said casing being expanded into a funnel shaped member, tubular members extending longitudinally within the casing and through 75 the wall of the car to the interior thereof, and means for collecting a portion of the air currents passing through the passage within the casing and causing them to enter the tubular members at a point at the rear of the point of entrance thereof into the car. 80

3. A car ventilator comprising a casing open at both ends and extending in the direction of travel of the car, tubular members extending longitudinally within the casing 85 and through the wall of the car to the interior thereof, each of said tubular members being formed with an opening in its side wall at a point at the rear of entrance thereof into the car, and hoods extending from 90 the rear of said openings and facing the direction of travel of the car for collecting a portion of the air currents within the casing and causing them to pass through the tubular member thereby creating a current 95 of air through said members from the car.

4. A car ventilator comprising a casing open at both ends and extending in the direction of travel of the car the front end of said casing being expanded into a funnel shaped member, tubular members extending longitudinally within the casing and through 100 the wall of the car to the interior thereof, each of said tubular members being formed with an opening in its side wall at a point 105 at the rear of entrance thereof into the car, and hoods extending from the rear of said openings and facing the direction of travel of the car for collecting a portion of the air currents within the casing and causing them to pass through the tubular member thereby creating a current of air through said members from the car. 110

5. A car ventilator comprising a casing open at both ends and extending in the direction of travel of the car, tubular members extending longitudinally within the casing and through the wall of the car to the interior thereof, each of said tubular members being formed with an elongated opening in 115 the walls thereof away from the side of the car, said opening being in the longitudinal portion of said tubular member at a point at the rear of the entrance thereof into the car, hoods flaring outwardly from the rear 120 of said openings and facing the direction of travel of the car for collecting a portion of the air currents within the casing and caus- 125

ing them to pass through said opening and
be deflected by the unbroken portion of the
tubular member opposite said opening thereby
by impinging upon the body of air in the
5 tubular member adjacent said opening and
causing it to move with said compressed currents by frictional engagement therewith.

In testimony whereof I affix my signature
in presence of two witnesses.
